(57) **CLAIM**

The ornamental design for a food container, as shown and described.

DESCRIPTION

The present application refers to a new and exclusive food container that consists specifically in a cookie tray in a doll format.

FIG. 1 shows a perspective view of the food container,

FIG. 2 shows an upper view of the food container,

FIG. 3 shows a bottom view of the food container,

FIG. 4 shows the side indicated by the arrow A of the FIG. 1 of the food container,

FIG. 5 shows the side indicated by the arrow B of the FIG. 1, wherein this view is a mirror image of the opposite side of said view of the food container; and,

FIG. 6 shows the side indicated by the arrow C of the FIG. 1 of the food container.
